CLAIM

The ornamental design for an electrode assembly as shown and described.

DESCRIPTION

The file of this patent contains at least one drawing/photograph executed in color. Copies of this patent with color drawing(s)/photograph(s) will be provided by the Office upon request and payment of the necessary fee.
FIG. 1 is a first front perspective view of an electrode assembly showing the claimed design;
FIG. 2 is a second front perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof;
FIG. 9 is an enlarged view of a portion of the first front perspective view enclosed by the shape 9 in FIG. 1;
FIG. 10 is an enlarged view of a portion of the left side view enclosed by the shape 10 in FIG. 5;
FIG. 11 is an enlarged view of a portion of the right side view enclosed by the shape 11 in FIG. 6;
FIG. 12 is an enlarged view of a portion of the top view enclosed by the shape 12 in FIG. 7;

FIG. 13 is an enlarged view of a portion of the top view enclosed the shape 13 in FIG. 8;
FIG. 14 is a first front perspective view of another example of an electrode assembly showing the claimed design;
FIG. 15 is a second front perspective view thereof;
FIG. 16 is a front view thereof;
FIG. 17 is a rear view thereof;
FIG. 18 is a left side view thereof;
FIG. 19 is a right side view thereof;
FIG. 20 is a top view thereof;
FIG. 21 is a bottom view thereof;
FIG. 22 is an enlarged view of a portion of the first front perspective view enclosed by the shape 22 in FIG. 14;
FIG. 23 is an enlarged view of a portion of the left side view enclosed by the shape 23 in FIG. 18;
FIG. 24 is an enlarged view of a portion of the right side view enclosed by the shape 24 in FIG. 19;
FIG. 25 is an enlarged view of a portion of the top view enclosed by the shape 25 in FIG. 20; and,
FIG. 26 is an enlarged view of a portion of the top view enclosed by the shape 26 in FIG. 21.

The broken lines in the drawings illustrate portions of the electrode assembly that form no part of the claimed design. The heavier weight dashed broken lines depict the boundaries of the enlarged views that form no part of the claimed design.
